APPARATUS FOR WINDING OR REELING CONTINUOUS STRANDS OF MATERIAL

Günther Werner, Reinbek, Hamburg, and Hugo Basler, Hamburg, Germany, assignors to Hanseatische Motoren-Gesellschaft m.b.H., Hamburg-Bergedorf, Germany

Filed Mar. 13, 1959, Ser. No. 799,135

6 Claims. (Cl. 242—54.4)

The invention relates to apparatus for winding or reeling strands of material and particularly to an automatic device by which a fibre strand, strip or sliver (for example, a carding sliver, a roving or a doubling) of the kind commonly encountered in the textile industries is wound upon a core and in which the supply of empty cores as well as the severance of the strip or sliver and the ejection of the completed winding is effected automatically.

In the known devices the fibre strip or sliver, the width of which is normally smaller than that of the coil to be produced, is wound upon the core until a previously determined and adjustable number of turns have been attained. Then the machine is stopped, the fibre strip or sliver severed and the finished winding removed manually or mechanically from the conveyor rolls and an empty core withdrawn from a magazine and fed to the conveyor rolls.

Substantial interruptions in operation are, however, involved in this procedure which cannot be compensated where a relatively high strip speed or winding speed is involved.

The invention, therefore, provides an automatic coil change device which is characterised by the fact that the coil change operation is effected by an electrical contact which co-operates with a magnetic clutch arranged in the winding assembly in such manner that the finished winding is transferred to an auxiliary roll before the severance of the fibre strip or sliver by means of a spring-loaded rocking arm, the auxiliary roll operating at the same peripheral speed or preferably at a higher speed than the conveyor or winding rolls used for producing the winding so that the oncoming strip is held under tension and can be severed by a spring-loaded striker lever whereby at the same time the continuing fibre strip is laid upon the new core fed to the winding rolls which is shifted with the increase in the radial dimension of winding by reason of its bearing moving in the vertical direction.

One constructional example of the invention is shown diagrammatically in side view in the accompanying drawings wherein:

Fig. 1 is a side view in one direction, and

Fig. 2 is a side view taken at 180° to Fig. 1.

A strip or sliver of fibrous material, not shown, arriving in the direction of the arrow P is wound on to a core 4 which rests on the conveyor or winding rolls 8, 9 between which the fibre strip or sliver passes, the said rolls being operatively connected one to the other and driven in suitable manner from a driving unit, not shown. This driving unit is based upon the normal practice and since the details thereof will be readily apparent to those skilled in the art, it has not been thought necessary to show the details of this driving mechanism.

In order to avoid any possible slip between the driving rolls 8, 9 and the finished winding 12, the core 4 is loaded at both ends by means of a forked loading device 13 in such manner that a uniform and always constant

2

pressure of the winding 12 or of the core 4 on the aforesaid rolls is secured during the winding operation. The loading device 13 is for this purpose pivotally mounted in the casing 17 about a pivot 13'.

5 The core 4 receiving the winding 12 is supported during the winding operation in the manner to be further described in such a way that it can follow the radial increase in the dimensions of the winding. As soon as it has reached a definite peripheral size, which is dependent 10 on the previously calculated and selected number of turns, the finished winding with the core is rocked away from the driving rolls 8, 9 and transferred to an auxiliary roll shown at 1.

For this purpose a magnetic clutch, not shown, is provided which is energised when the desired peripheral dimensions of the roll are reached, by means of which an electrical contact and the coil change operations forming an important part of the present invention come into operation, the operations being as follows:

20 The electrically-operated magnetic clutch provides the operative connection between the winding mechanism and the driving assembly whereby both the two cam discs 15 and 16 (Fig. 2) and also the auxiliary roll 1 are set into operation. The cam discs 15 releases through a roller 15' a rocking lever 2 which holds the core 4 at both ends in a slidable manner such that during the 25 winding on, the continuously increasing winding 12 is free to expand.

The lever 2 with the winding 12 on the core 4 now 30 tilts by means of a spring 17' into the dotted position shown in Fig. 1 so that the winding 12' comes into engagement with the auxiliary roll 1 and the core 4 at both ends comes into engagement with a hinged flap shown at 5. At the same time by the rocking of the 35 lever 2 an empty core 4' comes from a magazine 7 into the region of the driving rolls 8, 9 by the fact that a push rod 6 hinged to the lever 2 opens a magazine flap 7' whereby the new core 4' to be wound rolls along a guide rail 7" by its own weight and reaches the working 40 position.

Furthermore, the rocking lever 2 operates the hinged flaps 5 already described by means of link rods 10 so that the hinged flaps move to the closed position indicated in dotted lines during this rocking movement of the lever, whereby the finished winding 12' remains initially 45 on the auxiliary roll 1 and is also driven by the rotary movement thereof.

The auxiliary roll 1 arranged according to the invention and preferably rotating more rapidly than the driving rolls 8 and 9 ensures that the fibre strip or sliver is pulled tight between the aforesaid rolls 8 and 9 on the one hand and the roll 1 on the other hand. The cam disc 16 which is also provided and is also in rotation releases a spring operated striker 11 mounted on a shaft 11', by suitable linkage not shown, by means of 50 a roller 16' which severs the tensioned fibre strip or sliver under the action of the spring 18. The striker 11 is also of curved formation as shown to lay the end of the oncoming fibre strip or sliver on the newly introduced core 4' on which the next winding is now to be 55 formed.

When the cam discs 15 and 16 have been rotated through a predetermined amount, the lever 2 and the striker 11 both move back to the starting position whereby the hinged flap 5 is opened by the linkage rods 10 60 so that the previously completed winding 12' is automatically released from the device.

On the completion of the coil change an electric contact is operated in a manner not shown and which is operated for example by the cam disc 15 whereby the magnetic clutch again disconnects the drive of the coil change mechanism from the drive shaft.

What we claim is:

1. An automatic reeling device for continuous strand material, comprising a pair of closely spaced driving rolls, an auxiliary driving roll arranged in spaced apart relation from said driving rolls and disposed parallel therewith, means for automatically feeding strand receiving cores to said driving rolls, lever means rockably mounted between said driving rolls and auxiliary roll to support a core fed to the driving rolls and the winding form thereon to be driven by said driving rolls, means responsive to the diameter of the strand material wound on said core to shift said lever in the direction of said auxiliary roll and means for severing said strand material after a new core has been fed to the driving rolls.

2. An automatic winding device for continuous strip material, comprising a pair of closely spaced driving rolls, an auxiliary driving roll arranged in spaced apart relation from said driving rolls and disposed parallel therewith, a magazine for holding a plurality of empty cores in stacked relation so that the lowermost core can be released and deposited between said driver rolls and on top of the strand material passing thereover, a lever adapted to support the core as it is being wound and arranged for rockable movement between the driver rolls and auxiliary roller, yielding spring means for urging said lever in one direction, means responsive to the increase in diameter of the material wound on said core for transferring the core and strand material wound thereon to a position in which the strand material is drivingly engaged by said auxiliary roller, a spring oper-

ated striker lever to sever the strand material after an empty core has again been deposited on said driver rolls and means for guiding said cores while being wound directly above said driver rolls to support the core and strand material wound thereon in driving relation with said driving rolls.

5 3. An automatic winding device as set forth in claim 2 wherein said supporting lever and striker lever are separately controlled and in which a cam disc is provided for actuating each of said levers.

10 4. An automatic winding device as set forth in claim 2 wherein means is provided for releasing the completely wound core from said rockably mounted support after the severance lever has been actuated.

15 5. An automatic winding device according to claim 2 including a push rod pivoted to the rocking lever and arranged to control the release of cores from said magazine one at a time for positioning between said driver rollers during the starting of a new winding operation.

20 6. In an automatic winding machine as set forth in claim 2 in which a weighted loading device is provided for exerting downward pressure on the core to frictionally hold the core and the strand material in driving engagement with the driving rollers throughout the entire winding operation and during the radial increase in diameter of the material wound on the core.
